(57) **CLAIM**

The ornamental design for a lidar, as shown and described.

DESCRIPTION

FIG. 1 is a top perspective view of a lidar, showing our new design according to a second embodiment.

FIG. 2 is a front view thereof.

FIG. 3 is a back view thereof.

FIG. 4 is a left view thereof.

FIG. 5 is a right view thereof.

FIG. 6 is a top view thereof; and,

FIG. 7 is a bottom view thereof.

The broken lines in the figures illustrate the portions of the lidar that form no part of the claimed design.
